A. HOLTZ.
LOCKING CLOSURE FOR CONTAINERS.
APPLICATION FILED JAN. 21, 1916.

1,207,044.

Patented Dec. 5, 1916.

August Holtz,
Inventor

By *Geo. F. Kimmel*
Attorney

UNITED STATES PATENT OFFICE.

AUGUST HOLTZ, OF GRANT PARK, ILLINOIS.

LOCKING-CLOSURE FOR CONTAINERS.

1,207,044.

Specification of Letters Patent.

Patented Dec. 5, 1916.

Application filed January 21, 1916. Serial No. 73,376.

To all whom it may concern:

Be it known that I, AUGUST HOLTZ, a citizen of Germany, residing at Grant Park, in the county of Kankakee and State of Illinois, United States of America, have invented certain new and useful Improvements in Locking-Closures for Containers, of which the following is a specification.

The present invention relates to containers and the like, and more particularly to new and useful improvements in locking closures therefor.

An object of this invention is to provide an improved removable closure for a receptacle which is capable of securement on the receptacle rendering the same air tight.

Another object of this invention is to construct a closure for containers, which when secured in position is air tight and non-rattling, and wherein the usual bail is modified to form means for clamping the closure in position and engageable by a suitable locking element.

A further object of this invention is to provide clamping means for forcing the closure into position on the container, and also to provide means for locking the closure.

Other objects and advantages will appear from the following detail description and the claims, taken with an inspection of the accompanying drawing, in which—

Figure 1 is a fragmentary side elevational view of the container showing a closure thereon embodying the improvements of my invention, Fig. 2 is a transverse vertical sectional view taken on line 2—2 of Fig. 1 and looking in the direction of the arrows, Fig. 3 is a similar view taken on the line 3—3 of Fig. 2 looking in the direction of the arrows, and Fig. 4 is a top plan view of my improved closure.

Referring more particularly to the drawing, wherein similar characters of reference designate like and corresponding parts throughout the various views, 1 designates a container body of the shape usually employed in milk cans and the like, having a neck 2 formed on the upper end thereof, said neck having the free marginal edge thereof bent outwardly to form an annular flange 3. The flange 3 is annularly depressed to provide a recess 4 for reception of a sealing washer 5 of rubber or the like.

55 The closure designated 6 in its entirety, comprises a body portion formed of a cir-

cular sheet 7 substantially concavo-convex in cross-section and provided with a peripheral flange 8. A collar portion 9 having an annular flange 10 on its outer marginal edge is carried by the sheet 7, the flanges 8 and 10 being coincidental and the faces thereof soldered or otherwise connected. A handle 11 is mounted on the closure to facilitate its removal at times. The collar 9 is receivable in the neck 2, in the same manner as the usual milk can covers are inserted, the flange 10 bearing upon the washer 5 and thereby rendering air tight the joint.

A strip 12 is arranged diametrically on the closure, the opposite extremities of said strip extending beyond the peripheral margin of the closure to provide arms 13, for a purpose hereinafter set forth. The ends of the strip are arranged between the flanges 8 and 10, the flange 8 being offset at 14 to accommodate the strip. A plurality of ears 15 are carried by the collar 9, the strip extending through apertures 16 in the ears, said ears coacting with the flanges 8 and 10 to frictionally engage the strip and prevent lateral movement of the same. If desired the strip may be offset, or soldered to the flanges to prevent its movement.

I provide means for clamping the closure in position. For this purpose a plurality of lugs 17 are carried by the neck 2 and provided with apertures 18 in which my improved clamp hereinafter described, is journaled. The lugs are offset as at 19 to lie free of the flanges 3, 8, and 10, a plurality of tongues 20 being formed on the lugs and bent upwardly to form a pair of seats 21 for reception of the arms 13.

My improved clamping means comprises 95 a bail 22 formed of a strand of wire bent on its extremities to provide cam portions 23 and journal portions 24. A hasp 25 is carried by the bail preferably at the intermediate portion thereof and may be engaged over a loop 26 through which may be arranged a padlock 27 of any desired type.

In use my improved closure is placed on the container, the collar 9 being introduced into the neck 2. The closure is now turned 105 until the arms 13 engage in the seats 21. The bail when unlocked is in an upright or vertical position, the cam portions 23 being remote from the arms 13. However, when the arms are in their seats the bail is moved 110 to the position shown in the drawing whereupon the cam portions will engage the arms

2

firmly clamping the closure in position. Twisting of the closure is rendered impossible by the seats 21 thereby rendering it practically impossible for the closure to become accidentally dislodged. The operation described in the foregoing is reversed for removing the closure.

It will be readily apparent that the bail may be formed of material other than wire, 10 and that the lugs 17 may be integrally formed with the neck 2 if desired without departing from the spirit and scope of my invention. It will be understood, of course, that the use of the present invention is not 15 limited to milk cans, but is capable of application to various types and structures of containers with slight modification.

From the above description taken in connection with the accompanying drawings, it 20 is thought that a clear and comprehensive understanding of the construction, operation and advantages of my invention may be had, and while I have shown and described my invention as embodying a specific structure, 25 I desire that it be understood that I may make such changes on said structure as do not depart from the spirit and scope of the invention as described.

What I claim as my invention and desire 30 to secure by Letters Patent is:

1. The combination with a container having a neck extending therefrom, of a closure having marginally arranged projecting arms, said neck having a bail thereon and 35 receiving recesses for said arms, said bail having cam portions for engagement with the arms to maintain the closure on the container.

2. The combination with a container having a neck thereon, provided with a flange, 40 of a closure for said container having a flange for engagement with first said flange, a bail on said neck, a plurality of arms extending from the closure and seats therefor

on said neck, said bail being formed with 45 cam portions for engagement with said arms, and locking means associated with the bail.

3. The combination with a container having a neck provided with an annular flange, 50 of a closure having a pair of arms extending therefrom, a pair of lugs on the neck, and a bail pivoted therein and having bearing and cam portions on its extremities, said cam portions being engageable with the arms 55 to clamp the closure on the container.

4. The combination with a container having a neck provided with an annular flange, 60 of a closure, said closure having a collar, a pair of ears mounted on the said collar in diametrically opposite relation, the said ears being provided with transverse openings, a strip, arm members formed on the opposite ends of said strip, the said arms extending through the openings in the ear members, a 65 pair of lugs mounted on the neck, said lugs being adapted to form seats for the arms, a bail mounted on said lugs, said bail being formed with cammed portions for engagement with said arms, and locking means as 70 associated with the bail.

5. The combination with a container having a neck thereon, provided with a flange, 75 of a closure for said container having a flange for engagement with first said flange, a plurality of arms extending from the closure, a pair of lugs mounted on the said neck, tongue members formed on the sides of said lugs and bent upwardly forming 80 seats to receive the said arms, a bail mounted on the said lugs, said bail being formed with cam portions for engagement with said arms, and locking means associated with the bail.

In testimony whereof I affix my signature 85 hereto.

AUGUST HOLTZ.
